UNITED STATES PATENT OFFICE.

ENGLY GILES KILLERBRUE, OF KENOSHA, WISCONSIN, ASSIGNOR TO JOSEPH A. PITTS, OF KENOSHA, WISCONSIN.

CHRISTMAS-TREE HOLDER.

No. 893,247.

Specification of Letters Patent.

Patented July 14, 1908.

Application filed February 4, 1907. Serial No. 355,576.

To all whom it may concern:

Be it known that I, ENGLY GILES KILLERBRUE, a citizen of the United States, residing at Kenosha, in the county of Kenosha and 5 State of Wisconsin, have invented certain new and useful Improvements in Christmas-Tree Holders, of which the following is a specification.

One of the objects of this invention is the 10 production of a strong, stable, and inexpensive stand or support which may be used for holding Christmas-trees and other objects.

Another object of the invention is the provision of means for readily securing the tree 15 or other object to the holder.

The accompanying drawing is a perspective view of a Christmas-tree holder embodying the features of my invention.

The preferred embodiment of my invention 20 comprises a base consisting of two side bars 1 connected together by means of two cross bars 2, said cross bars being spaced a suitable distance apart and secured to the side bars 1 by means of nails 3 or other suitable fastening devices. To add to the rigidity 25 of the structure, I may place filler blocks 4 between the ends of the cross bars 2, said filler blocks being nailed or otherwise secured to the side bars 1. The side bars 1 and 30 cross bars 2 are of sufficient length to afford a stable support for the object to be held.

In practice the holder is made in several sizes for use with various sizes of Christmas-trees. I prefer that the lower edges of the 35 cross bars 2 shall not be flush with the lower edges of the side bars 1 in order that the

holder may be the more easily placed firmly upon an uneven floor or other support. One of the cross bars 2 carries the means for attaching the tree *a* to the holder. Said attaching means in this embodiment comprises a **U**-shape bolt 5, the legs of which extend through openings 6 in said cross bar, wing nuts 7 being turned upon the screw-threaded outer ends of said legs. The tree is clamped 45 by said bolt against a seat block 8 suitably secured to the cross bar 2, said seat block being recessed as by forming a **V**-groove 9 therein to receive the stem of the tree. The seat block 8 may be made of suitable length 50 to afford a good bearing upon the object to be held. In use, the **U**-bolt 5 is slackened sufficiently to receive the butt of the tree between its legs and said bolt drawn up to clamp the tree against the seat block 8. 55

The foregoing detailed description is given for clearness of understanding only, and is not to be regarded as in the nature of an undue limitation.

I claim as my invention:

A supporting device, comprising vertically arranged side members, vertically arranged tie members connecting said side members and having their lower edges above the plane of the lower edges of said side members, and 65 a tree attaching means on the side of one of said tie members.

ENGLY GILES KILLERBRUE.
